UNITED STATES PATENT OFFICE.

WILHELM JOHANNES MENNES, OF AMSTERDAM, NETHERLANDS.

DEVICE FOR SUPPORTING THE HANDS OF PIANO-PLAYERS.

SPECIFICATION forming part of Letters Patent No. 653,814, dated July 17, 1900.

Application filed February 20, 1900. Serial No. 5,957. (No model.)

To all whom it may concern:

Be it known that I, WILHELM JOHANNES MENNES, teacher of music, a subject of the Queen of the Netherlands, residing at 137 5 Govert Flinck-straat, Amsterdam, Netherlands, have invented a certain new and useful Device for Supporting the Hands of Pianoforte-Players, of which the following is a specification, reference being had to the accompanying drawings, in which—

Figure 1 shows the arm-band with the elastic band secured thereto. Fig. 2 shows the hook which transfers the pull of the band to the hand in side elevation and plan, while Fig. 15 3 shows the application of the device to a left hand.

This invention relates to a device which is designed to insure the correct position of the hands or fingers in playing the pianoforte 20 and may be known by the name "Lassa."

As is known, the correct position of the hands is one of the essential conditions for good pianoforte-playing. Experts are agreed that the correct position is that in which the 25 back of the hand is somewhat inclined from the little finger to the thumb. The thumb remains straight, while the fingers from the second joint down are drawn in, which gives the hand a gentle curvature. Any one who 30 has occupied himself in pianoforte exercises knows how difficult it is to accustom oneself to this correct position of the hands. Only after years of practice is it possible to attain any proficiency in this respect, and many persons otherwise highly gifted lose their interest in playing the pianoforte because of not 35 succeeding in acquiring the indispensable "execution," and execution—that is to say, the power of pressing the correct keys rapidly, surely, and in the prescribed manner—can only be attained if the learner in his exercises holds his hands in the correct position. In the normal position of the hands the inclination is, however, in the opposite 40 direction, the thumb being thus higher than the little finger. Accordingly a certain tension of the muscles is required in order to prevent the hand from going back out of the correct into the normal position, and so long 45 as these muscles are not hardened by years of exercise fatigue will very soon be caused thereby.

My invention is designed to produce a device whereby the pianoforte-player is forced to keep the hands always steadily in the correct position, without, however, being in any way impeded in his movements. This is effected by assisting and to some extent replacing the muscular power which must be exerted in order to keep the hands continuously in the correct position by the elastic power of a band. For this purpose there is placed around the forearm, approximately in the middle between the wrist and the elbow, a band, preferably an elastic band in order 55 to be able to fit any circumference of arm. From this band a second band, which is also elastic, extends around the arm to the side of the thumb, then over the back of the hand, and is finally detachably fastened to a hook 60 65 which is placed around the hand at the side of the little finger.

In Fig. 1, *a* is a broad band which is provided with a buckle *b* and an adjusting-slide *c*. On this band *a* is secured a fastening 75 spring or clip *d*. Through this spring or clip *d* is drawn one end of the elastic band *e*, which is provided at its other end with a small hook *f*. The wires or threads of the material of the band *e* are longer at the outer 80 side of the band than at the inner side, so that the band fits the arm and hand well.

The hook *g*, Fig. 2, at the place where it comes into contact with the hand is covered with a piece of leather *h* in order to prevent 85 the sharp edges of the hook from pressing into the hand.

Fig. 3 shows the several parts in their interconnection when the device is in use.

The two bands *a* and *e* can be lengthened or 90 shortened, as desired—as regards the band *a* by means of the adjusting-slide *c* and the band *e* by drawing it more or less through the spring or clip *d* and then fastening the spring or clip.

As shown in Fig. 3, the band *e* is adjusted around the arm and hand and the hook *g* arranged so that the wrist-joint *i* and the joint *k* of the little finger remain free.

The operation of the apparatus is as follows: The above-described position of the hands is produced and maintained by the drawing action of the band *e* without the player being required to exert himself. The

elasticity of the band *e* replaces the work which would otherwise have to be performed by the muscles. The band *e* rests on the back of the hand, between the wrist-joint and the joint 5 of the little finger, and therefore the free movement of the hand is in no way interfered with.

In order to remove or throw the device out of action, it is only necessary to pull the band 10 *e* at the free end *f*. The hook *f* is then released from the hook *g*, whereupon the hand is immediately quite free. The two hooks *f* and *g* can be again connected quite as quickly and easily, and the device thus brought into 15 action.

The results which are attained with my improved hand-supporting device are wonderfully good.

The player's hand, while being unimpeded, 20 is constantly maintained in the correct position, and after exercises have been played one hour per day for a month with this device it can be perceived that one's execution has considerably improved, and in time the 25 device can be dispensed with entirely. The position of the player is quiet and the touch powerful and certain.

What I claim is—

1. In a hand-supporting device for piano-forte-players the combination of a hook shaped to embrace the side of the hand near the joint of the little finger, a band adapted to be secured around the forearm, and an elastic band detachably connected at one end to the 30 aforesaid hook and arranged to be wound around the forearm and adjustably secured at 35

its other end to the said band secured around the forearm, substantially as described, and for the purpose specified.

2. In a hand-supporting device for piano-forte-players, the combination of a hook shaped to embrace the side of the hand above the joint of the little finger, a band adapted to be secured around the forearm, and an elastic band detachably connected at one end to the 40 said hook and arranged to be passed over the back of the hand, under the wrist, and then over the back of the forearm attached to the band secured around the forearm, substantially as described, and for the purpose specified. 45

3. In a hand-supporting device for piano-forte-players, the combination of an arched hook shaped to embrace the side of the hand above the joint of the little finger and carrying 50 a pad *h*, an elastic band adapted to be secured around the forearm, another elastic band detachably connected at one end to the said hook and arranged to be passed over the back of the hand between the wrist-joint and the joint of 55 the little finger and under the wrist and then over the back of the forearm, said band being attached by a clip to the band secured around the forearm, substantially as described, and for the purpose specified. 60

In witness whereof I have hereunto set my hand in presence of two witnesses.

WILHELM JOHANNES MENNES.
